WHEELBARROW

Filed Nov. 7, 1927

UNITED STATES PATENT OFFICE

JOHN CWIK, OF CHICAGO, ILLINOIS

WHEELBARROW

Application filed November 7, 1927. Serial No. 231,714.

My invention relates to improvements in wheelbarrows, and it consists in the combinations, constructions, and arrangements herein described and claimed.

5 The invention relates particularly to that type of wheelbarrow in which an auxiliary rear wheel is provided in addition to the ordinary front wheel for relieving the operator of a portion of the load, but which is 10 adjustable so as to support the rear end at various heights. In certain devices of the type mentioned, it is necessary to use both hands to effect the adjustment. In other devices, the adjusting mechanism is complex 15 and not only adds to the weight but to the expense of the device.

An object of my invention is to provide a wheelbarrow having an adjustable rear wheel which may be adjusted and locked in its 20 adjusted position without the necessity of releasing the grip of the hands on the handles, thereby permitting the adjustment to be made while the load is raised, as in the act of propelling the wheelbarrow.

25 A further object is to provide a device which is light in weight, simple in construction, positive in action, and is relatively inexpensive to manufacture.

A further object is to provide a device 30 which will not at all interfere with the ordinary operation of the wheelbarrow, as, for instance, where one, after unloading the wheelbarrow, returns to the loading position by pulling the wheelbarrow while facing to 35 the rear between the handles, as in drawing a cart.

A further object of my invention is to provide a device by means of which the adjustment and the locking of the auxiliary wheel 40 in its adjusted position may be almost instantly effected.

Other objects and advantages will appear in the following specification, and the novel 45 features of the invention will be particularly pointed out in the appended claim.

My invention is illustrated in the accompanying drawings, forming part of this application, in which

50 Figure 1 is a side elevation of my device,

Figure 2 is a sectional view taken along the line 2—2 of Figure 1, and

Figure 3 is a sectional view taken along the line 3—3 of Figure 1.

In carrying out my invention, I provide 55 a main frame comprising the longitudinal members 1 and 2 which are angularly inclined toward each other, the ends of these members being preferably rounded to constitute handles 1^a and 2^a, respectively. At 60 3 I have shown a cross member which holds the members 1 and 2 in spaced relation. Mounted on the members 1 and 2 and secured thereto is a receptacle 4 for carrying loads. This may be of any suitable shape, such as 65 that shown in the drawing. Secured to the members 1 and 2 at their upper ends are brace members 5 and 6. These are connected at their bottoms, as shown in Figure 1, which, together with inwardly extending flanges 5^x 70 at their bottoms, constitute legs for supporting the device when at rest. A brace rod 7 is disposed between the members 6 to strengthen the device. The front wheel 8 is pivotally mounted at 9 between the ends of 75 the members 1 and 2.

The description thus far is that of the ordinary wheelbarrow. The invention lies in the provision of an auxiliary rear wheel 10 which is pivotally mounted at 11 between 80 strips 12 which are carried by a slidably post 13. The latter, as will be observed, is preferably rectangular in cross section and is arranged to pass through an opening 14 in the cross member 3. This post is provided with 85 a series of openings 15 extending transversely of the longitudinal axis of the device.

Pivotally secured to the brace members 6 at 6^x are curved links 16 whose inner ends are pivotally secured to the strips 12 at the central axis of the auxiliary wheel 10. This permits the auxiliary wheel to move bodily about the point 6^x as a center and to facilitate this movement the upper portion of the post 13 is curved, as shown in the drawings.

A locking arm 17 is slidably disposed in bearings 18 carried by the cross member 3. This locking arm has secured to it a collar 19, and between this collar and a similar collar 20 loosely carried by the arm 17 is a spiral 100

spring 21. A lever 22 is pivotally mounted at 23 on a bracket 24 carried by one of the side members, such as the right-hand side member 2. This lever is pivotally connected at 25 to 5 the end of the locking arm 17. In order to protect the spring and the locking arm, I preferably provide a housing 26.

From the foregoing description of the various parts of the device, the operation thereof 10 may be readily understood. When the wheelbarrow is being filled, the auxiliary wheel is designed to be in a position just level with the bottom of the legs, where it is held by means of the locking arm which projects 15 through one of the openings 15. When the operator is ready to proceed with his load, he may raise the handles as in the ordinary manner of propelling the wheelbarrow and then without shifting his grip press on the 20 end of the lever, when the post with the auxiliary wheel will fall down by gravity until it has reached the ground and the device may be wheeled on the two wheels, thus relieving the operator of a portion of the load.

25 If it is desired to raise the auxiliary wheel, the lever is pressed, freeing the locking arm, and then all that is necessary is to lower the handles to the position desired, release the lever, whereupon the locking arm will spring 30 into the opening at this height so that when the handles are again raised into the ordinary propelling position, the auxiliary wheel will be raised so as to permit the operation of the device as in the ordinary wheelbarrow.

35 It will be noted that there are no parts between the handles to interfere with the operation, and, when the load is dumped, the operator may reverse his position and get between the handles and draw the wheelbarrow back- 40 wardly as a cart is drawn.

I claim:

A wheelbarrow comprising a frame having handle portions a receptacle carried thereby, a front wheel, legs secured to the frame, a 45 post, slidably disposed with respect to the frame and being provided with a plurality of openings, an auxiliary wheel carried at the lower end of said post, links pivotally secured to said legs and to the lower end of said post, 50 a slidably locking arm arranged to enter the openings in the post, a spring for forcing the arm toward the post, and a lever pivotally mounted on one of said handles and being pivotally connected to said arm for withdraw- 55 ing the arm against the tension of the spring to release the post, whereby the position of the auxiliary wheel with respect to the frame may be shifted and the auxiliary wheel locked or unlocked in its shifted position.

60 Signed at Chicago, in the County of Cook, and State of Illinois, this 27 day of October, A. D. 1927.

JOHN CWIK.
